CLAIM

I claim the ornamental design for a child monitoring device, as shown and described.

DESCRIPTION

FIG. 1 is a top front isometric view of a child monitoring device showing my new design;

FIG. 2 is a bottom front isometric view of a child monitoring device showing my new design;

FIG. 3 is a top plan view thereof;

FIG. 4 is a bottom plan view thereof;

FIG. 5 is a front elevation view thereof;

FIG. 6 is a rear elevation view thereof;

FIG. 7 is an enlarged, left side elevation view thereof; and,

FIG. 8 is an enlarged, right side elevation view thereof.
